[57] CLAIM

The ornamental design for vacuum cleaner, as shown and described.

DESCRIPTION

FIG. 1 is a front elevational view of a vacuum cleaner showing our new design;

FIG. 2 is a right side elevational view thereof;

FIG. 3 is a left side elevational view thereof;

FIG. 4 is a top plan view thereof;

FIG. 5 is a rear elevational view thereof;

FIG. 6 is a bottom plan view thereof;

FIG. 7 is a front elevational view of a second embodiment thereof, the undisclosed right, left, top, rear and bottom views are identical with FIGS. 2, 3, 4, 5 and 6; and

FIG. 8 is a right side elevational view thereof.

The hose is shown in partial broken lines in FIGS. 1, 2, 3, 5 & 7 for ease of illustration only and is understood to repeat uniformly throughout the indicated area.

FIG. 1

FIG. 2

FIG. 3

FIG. 5

FIG. 4

FIG. 6

FIG. 7

FIG. 8
